UNITED STATES PATENT OFFICE.

ELIJAH TOLMAN, JR., OF TAUNTON, MASSACHUSETTS.

IMPROVEMENT IN LAMP-CHIMNEYS.

Specification forming part of Letters Patent No. 178,089, dated May 30, 1876; application filed April 18, 1876.

To all whom it may concern:

Be it known that I, ELIJAH TOLMAN, Jr., of Taunton, Bristol county, Massachusetts, have invented a new and Improved Lamp-Chimney, of which the following is a specification:

The invention is an improvement in the class of lamp-chimneys which are provided with a hole for insertion of a match or taper for lighting the lamp. The improvement relates to the means or mode of attaching the cover of the hole to the chimney, as hereinafter described.

Figure 1 is a side elevation of a lamp-chimney having an opening for lighting it contrived according to my invention. Fig. 2 is a section on line *x x*.

A is the chimney; *B*, the hole for the match; *C*, the eyelet for attaching the cover *D*. The

eyelet *C* is fitted in the hole, and from it extends an arm or shank, *E*, downward to form a support for the cover, the shank or stem *G* of which is pivoted to it at *F*. This arm *E* and the stem *G* are set so as to spring the cover into the hole a little, and the cover is made convex on the side pressing against the eyelet *C*, to adapt it to close the hole tight.

What I claim is—

The combination, with the chimney, of the eyelet *C*, provided with arm *E*, and the cover having shank *G*, by which it is pivoted to said arm, as shown and described.

ELIJAH TOLMAN, JR.
